UNITED STATES PATENT OFFICE.

WILLIAM A. SHORB, OF DECATUR, ILLINOIS.

PIPE-REAMER.

SPECIFICATION forming part of Letters Patent No. 594,914, dated December 7, 1897.

Application filed March 20, 1897. Serial No. 628,473. (No model.)

To all whom it may concern:

Be it known that I, WILLIAM A. SHORB, of Decatur, in the county of Macon and State of Illinois, have invented certain new and useful Improvements in Pipe-Rreamers, of which the following is a specification.

The reduction of bore caused by the bur made in cutting off iron pipe with the ordinary tools has been found to impair the efficiency of steam and hot-water heating apparatus and to reduce the flow through the service-pipes of a building; and it is the object of this invention to provide a cheap and effective device that will remove the bur from pipes of all ordinary sizes, that may be guided accurately while in operation, and that will stand the rough usage commonly given tools by workmen.

The invention is exemplified in the structure hereinafter described, and it is defined in the appended claims.

In the drawings forming part of this specification, Figure 1 is a side elevation of a reamer constructed in accordance with my invention. Fig. 2 is a section on line X in Fig. 1. Fig. 3 is a view of the reamer with the point thereof presented toward the observer.

The reamer consists of a skeleton frame, cutters in the frame, a guide-handle, and a wrench, each of which has peculiarities as follows: A set of three triangularly-disposed ribs 2 project convergingly from the outer edge of the lower face of a circular disk 1, their lower ends meet and merge, as shown at 14, and they are grooved longitudinally in their outer surfaces. A boss 3, square or otherwise prismatic in cross-section, rises rigidly from the center of the upper surface of the disk, and it is bored axially to receive the reduced shaft 6 of the shank 4 of guide-handle 5. These features constitute the frame, and they are preferably embodied all in one casting. The wrench-head 9 is shaped to conform to the prismatic boss 3, over which it fits, as shown in Fig. 1, and it has a suitable handle, as 10. The guide-handle 5 has a shank 4, which extends in line with the axis of the frame, and the lower end of the shank is reduced to form a shoulder and produce shaft 6. The shoulder bears against the upper surface of the wrench-head, and

the shaft extends through the wrench-head and through the boss and projects into the space defined by ribs 2. A washer 8 fits over the downward-extended end of shaft 6, and a key 7 is set through the shaft below the washer and holds the wrench and the guide-handle in operative connection with the frame. A cutter-blade 11 is set into the groove of each of the ribs 2 and held therein by means of a split key 13, for instance. The cutters are longer than the ribs, and they extend some little distance below the lower or conjoined ends of the same. The grooves meet at a point in the conjunction of the ribs, and the inner edges of the cutters follow the bottoms of the grooves to the meeting-point. From the meeting-point on downward they back one against the other in lines parallel with the axis of the rib-frame, and the contiguous surfaces of the blades each form, in end view, an angle of one hundred and twenty degrees, as shown in Fig. 3. This causes the backs of the lower ends of the blades to nest together like hexagonal bodies, and each two form a groove in which the other one is held against lateral displacement. The blades are made of steel, their sides are parallel for a distance corresponding to the length of the ribs, their cutting edges are beveled to present sharper surfaces to the work, and the extending ends 12 are cut away to increase the abruptness of the taper of the cutter taken as a whole.

In operation the guide-handle is grasped by the left hand, the wrench-handle is held by the right hand, and the cutter blades are inserted into an end of a pipe. The guide-handle is then held in such manner that the axis of the cutter shall coincide with the axis of the pipe, slight pressure is applied, and the wrench is swung back and forth in an arc of at least one-third of a circle.

The cutter-blades are applicable to a very small pipe, the guide-handle in line with the axis of the cutting-frame enables the device to be accurately operated, the triangular arrangement of the ribs permits access to the lower end of shaft 6, and the use of three cutters insures the operation of each under all circumstances.

By making the device of malleable iron stability and durability to a high degree may

be attained, there are no delicate parts to break or become detached and mislaid, and the expense of construction is small.

What I claim as new, and desire to secure 5 by Letters Patent, is—

1. A pipe-reamer consisting of a disk, a set of grooved ribs converging from a side of the disk and merging one into the other, a prismatic boss extending from the center of 10 the disk on the side opposite the ribs, a wrench fitting onto the boss, a guide-shaft extended through the boss and into the space defined by the ribs, a fastening on the guide-shaft in the space defined by the ribs, and 15 cutter-blades in the grooves of the ribs, substantially as set forth.

2. A pipe-reamer consisting of a disk, a set of grooved ribs converging from a side of the disk and merging one into the other, a 20 prismatic boss extending from the center of the disk on the side opposite the ribs, a wrench fitting around and against the end of the boss, a guide-shaft extending through the wrench-head and through the boss and 25 having a shoulder bearing against the wrench-

head, a fastening on the guide-shaft in the space defined by the ribs, and cutter-blades in the grooves of the ribs, substantially as set forth.

3. A tapered pipe-reamer having three longitudinal grooves meeting at the apex of the reamer, and a cutter-blade in each groove extending beyond the meeting-point and backing one against the other, substantially as set forth. 30

4. A tapered pipe-reamer having three longitudinal grooves meeting at the apex of the reamer and a cutter-blade in each of the grooves, said blades extending beyond the meeting-point of the grooves, backing one 40 against the other throughout the extensions, and being cut away to increase the abruptness of the taper near their points, substantially as set forth. 35

In testimony whereof I sign my name in 45 the presence of two subscribing witnesses.

WILLIAM A. SHORB.
